H. O. SHORT

WING AND LIKE MEMBER CONSTRUCTED OF METAL FOR AEROPLANE

FLYING MACHINES AND OTHER AIRCRAFT

Filed Sept. 11, 1922

—FIG. 1.—

—FIG. 2.—

—FIG. 3.—

—FIG. 4.—

Hugh Oswald Short
Inventor
By J. D. E. Lund, Reg.

UNITED STATES PATENT OFFICE.

HUGH OSWALD SHORT, OF ROCHESTER, ENGLAND.

WING AND LIKE MEMBER CONSTRUCTED OF METAL FOR AEROPLANE FLYING MACHINES AND OTHER AIRCRAFT.

Application filed September 11, 1922. Serial No. 587,561.

To all whom it may concern:

Be it known that I, HUGH OSWALD SHORT, a subject of the King of Great Britain, residing at Norfolk Lodge, Borstal 5 Road, Rochester, Kent, England, have invented certain new and useful Improvements in Wings and like Members Constructed of Metal for Aeroplane Flying Machines and Other Aircraft, of which the following is a specification.

Metal wings and like members (hereafter termed wings) for aeroplane flying machines and other aircraft, are composed of a framework which is covered above and below by a sheet metal covering. Such framework comprises metal girder structures, which are connected together in some suitable manner, and the outer covering of sheet metal is composed of a plurality of sheets which are connected together and to the framework, and consequently the thin sheet metal covering spans the distance between one such girder structure of the framework and the next adjacent girder structure.

The primary object of the present invention is to provide means for efficiently supporting and stiffening those parts or portions of the thin sheet metal covering which extend between one girder structure and the next, so as to resist stresses tending to buckle or bend such portions of the sheet metal covering intermediate between the supporting girders or ribs, and to do this without multiplying those interior girder structures, commonly termed ribs, which extend between the interior surfaces of the sheet metal covering of the wing.

The invention further refers to the combination of the means for supporting and stiffening the sheet metal covering, with a particular construction of the supporting frame and covering of a wing to which the invention is particularly suited.

According to this invention the sheet metal covering which is fixed to the girder structures of the framework is divided between each two of said girder structures, the adjacent edges of said sheet metal covering at said division having flanges at right angles to its surface. Between these flanges the edge of a fin of sheet metal is interposed, the fin extending a short distance into the interior of the wing, and the flanges of the sheet metal covering at the

division thereof and the edge of the said fin which is interposed between said flanges are then fixed together by riveting or the like.

According to the preferred construction the sheet metal wings comprise a plurality of thin sheet metal ribs at requisite distances apart shaped to the requisite wing section and extending parallel with the direction of flight, spars extending through said ribs transversely to the line of flight 60 to support said ribs, and thin sheet metal covering strips extending in the direction of the line of flight, each outwardly flanged at both its edges and adapted to fit between said ribs and be secured thereto to constitute the wing covering, and according to the present invention each of said covering strips is divided between said ribs in the direction of the line of flight, said divided edges being outwardly flanged, and the sheet metal fins are interposed between said flanges at the divided edges of said covering strips, said fins extending inwardly into the interior of said wing, said flanges at the divided edges of the covering strips and the interposed fin being riveted together to strengthen the sheet metal covering between the ribs.

The invention will be described with reference to the accompanying drawings, 85 whereon Fig. 1 shows a vertical section of a portion of a wing taken in a plane transversely of the line of flight, the section being taken about the line X—Y of Fig. 2, and Fig. 2 is a part plan view drawn to a 90 smaller scale than Fig. 1.

Fig. 3 is a detail view drawn to a larger scale, showing a fin according to this invention and its connection with the covering strips, and Fig. 4 is a view similar to Fig. 3, 95 showing a slightly modified construction.

Referring to Figs. 1 and 2, the wing comprises ribs 1 constructed of sheet metal, which are supported at the requisite distances apart upon front and rear spars 2, 3, 100 the ribs 1 being of the requisite shape of the wing section, arranged parallel to each other at distances apart and extending parallel to the line of flight. The sheet metal covering of the wings extends parallel to the direction 105 of flight, and such covering according to this invention is divided into strips such as 4 and 5. The covering strips 4 and the covering strips 5 are flanged at their edges adjacent the ribs 1, the flanges extending pref- 110

erably outwardly as shown, and the flanges of adjacent covering strips contact with the ribs 1 at the edges thereof, and the joint is usually covered by a channel section strip 5 of metal 6, the channel section strip 6, the adjacent flanges of the strips 4 and 5, and the edges of the rib 1 being riveted together.

Intermediate between the ribs 1, the strips 10 4 and 5 are also flanged, as shown for instance at 7 Fig. 3, and between the flanges 7 the edge of a fin 8 is inserted, the fin extending for a short distance into the interior of the wing, and the joint between the flanges 15 of the covering strips 4 and 5 and the fin is usually covered by a channel section strip 9, and rivets pass through the channel section strip 9, through the flanges of the covering strips 4 and 5, and through the edge of the 20 fin 8. The end of the fin 8 which projects into the interior of the wing may be formed with a flange 10 extending at right angles to the fin, or with any other suitable formation.

25 Instead of fitting a channel section strip, such as 9, to cover the joint, one of the flanges such as 7^x (Fig. 4) of the covering strip 4 may be extended and bent over to cover the joint between the flanges of the 30 strips 4 and 5 and the fin 8.

Obviously more than one fin may be fitted between the adjacent ribs 1, and in the drawing at Fig. 1, by dotted lines, two further fins 11 are indicated, and similar fins are 35 fitted to the metal covering strips on the under side of the wing.

What I claim as my invention and desire to secure by Letters Patent is:—

1. In wings and the like members constructed of sheet metal for aeroplane flying machines and other aircraft; the combination with a framework comprising metal ribs, and means for connecting together said ribs; of an external sheet metal covering, 40 means for connecting said sheet metal covering to said ribs, said sheet metal covering having a division between each two of said ribs of said framework, the adjacent edges of said sheet metal covering at said division 45 having flanges at right angles to its surface, a fin of sheet metal located between said flanges of said covering and extending a short distance into the interior of said wing, and means for connecting together the 50 flanges of said sheet metal covering and the edge of said fin interposed between same.

2. In wings and the like members constructed of sheet metal for aeroplane flying machines and other aircraft; the combination with a framework comprising sheet metal ribs of the requisite wing section parallel to each other and extending parallel to the line of flight, and spars extending transversely and passing through said ribs 60 to support same; of thin sheet metal cover- 65

ing strips extending in the direction of the line of flight, outwardly extending flanges at both edges of said covering strips to fit between said ribs to constitute a wing covering, rivets to connect said adjacent flanges 70 of adjacent covering strips and the edges of said ribs interposed between same, each of said covering strips having a division between said ribs in the direction of the line of flight, the edges of said divisions of said 75 covering strips having outwardly extending flanges, sheet metal fins interposed between said flanges at said divided edges of said covering strips, said fins extending inwardly into the interior of said wing, and means for fixing together said flanges at said divided edges of said covering strips and said interposed fin to strengthen said sheet metal covering between said ribs. 80

3. In wings and the like members constructed of sheet metal for aeroplane flying machines and other aircraft; the combination with a framework comprising sheet metal ribs of the requisite wing section parallel to each other and extending parallel to 85 the line of flight, and spars extending transversely and passing through said ribs to support same; of thin sheet metal covering strips extending in the direction of the line of flight, outwardly extending flanges at 90

both edges of said covering strips to fit between said ribs to constitute a wing covering, rivets to connect said adjacent flanges of adjacent covering strips and the edges of said ribs interposed between same, each of 95 said covering strips having a division between said ribs in the direction of the line of flight, the edges of said divisions of said covering strips having outwardly extending flanges, sheet metal fins interposed between 100 said flanges at said divided edges of said covering strips, said fins extending inwardly into the interior of said wing, means for externally covering the joint between said flanges of said covering strips and said fin, and means for fixing together said flanges at said divided edges of said covering strips and said interposed fin to strengthen said sheet metal covering between said ribs. 105

4. In wings and the like members constructed of sheet metal for aeroplane flying machines and other aircraft; the combination with a framework comprising sheet metal ribs of the requisite wing section parallel to each other and extending parallel to the line of flight, and spars extending transversely and passing through said ribs to support same; of thin sheet metal covering strips extending in the direction of the line of flight, outwardly extending flanges at 110 both edges of said covering strips to fit between said ribs to constitute a wing covering, rivets to connect said adjacent flanges of adjacent covering strips and the edges of 115 said ribs interposed between same, each of 120 said covering strips having a division between said ribs in the direction of the line of flight, the edges of said divisions of said covering strips having outwardly extending flanges, sheet metal fins interposed between 125 said flanges at said divided edges of said covering strips, said fins extending inwardly into the interior of said wing, means for externally covering the joint between said flanges of said covering strips and said fin, and means for fixing together said flanges at said divided edges of said covering strips and said interposed fin to strengthen said sheet metal covering between said ribs. 130

said covering strips having a division between said ribs in the direction of the line of flight, the edges of said divisions of said covering strips having outwardly extending flanges, sheet metal fins interposed between said flanges at said divided edges of said covering strips, said fins extending inwardly into the interior of said wing, a channel section strip of sheet metal to cover the joint between said flanges of said covering strips and said fin, and means for fixing together

said channel section strip, said flanges at said divided edges of said covering strips, and said interposed fin to strengthen said sheet metal covering between said ribs. 15

In witness whereof I have hereunto set my hand in the presence of two witnesses.

HUGH OSWALD SHORT.
